UNITED STATES PATENT OFFICE

STACY B. HASELTINE, OF CHICAGO, ILLINOIS, ASSIGNOR TO W. H. MINER, INC., OF CHICAGO, ILLINOIS, A CORPORATION OF DELAWARE

CAR CONSTRUCTION

Application filed January 24, 1929. Serial No. 334,691.

This invention relates to improvements in car construction.

One object of the invention is to provide means for connecting the body and truck bolsters of a railway car to prevent separation of the bolsters, especially in the event of collision, and thereby eliminate the danger of telescoping of cars, the connecting means being in the form of a multipart center pin, certain members of which have shouldered engagement with the bolsters, the last named members of the pin being collapsible to permit assembling thereof by insertion through the center pin receiving openings, the parts being held in expanded condition by a filler member or spreader to maintain the shouldered engagement between the pin and the bolsters, the assembled members of the pin together forming a retaining element of exceptionally large cross sectional area at the co-operating center bearing portions of the two bolsters to effectively resist shearing action.

A more specific object of the invention is to provide a center pin construction for connecting the body and truck bolsters of railway cars, including two outer members together forming a tubular connecting element, and a central filler member, the latter holding the outer members of the pin expanded, the two outer members each being headed at opposite ends and having shouldered engagement with both bolsters, said outer members at one end portion of the pin having contact with each other along their inner sides when assembled with the bolsters, and being cut away on their inner sides at the other end portion of the pin to allow contraction of the head portions at said end to permit insertion through the center pin openings of the bolsters.

A still further object of the invention is to provide a center pin connection for the body and truck bolsters of railway cars, wherein the pin is of the character hereinbefore indicated, is relatively short and has shouldered engagement with both bolsters at closely adjacent points, thereby providing a rugged locking element which may be readily assembled with the bolsters.

Other and further objects of the invention

will more clearly appear from the description and claims hereinafter following.

In the drawing, forming a part of this specification, Figure 1 is a top plan view of a portion of the body bolster of a railway car, illustrating my improvements in connection therewith. Figure 2 is a vertical sectional view through the body and truck bolsters of a car, corresponding substantially to the line 2-2 of Figure 1. And Figure 3 is a horizontal sectional view, partly broken away, corresponding substantially to the line 3-3 of Figure 2.

In said drawing, 10 indicates generally the body bolster of a railway car and 11 a portion of the co-operating truck bolster. The body bolster 10 is provided with the usual top and bottom web portions connected by a cylindrical sleeve section 12 which accommodates the center pin. The bottom web of the bolster is provided with the usual bearing projection 13 which is formed integral with the sleeve 12 and has a spherical bottom bearing surface 14 which cooperates with a spherical bearing surface 15 formed on a bearing block 16 seated in a pocket 17 provided at the top of the truck bolster 11.

As most clearly shown in Figure 2, the bearing block 16 is provided with an upstanding annular flange 18 which extends into a pocket or opening 19 formed at the bottom of the body bolster. The truck bolster is also provided with the usual top and bottom web portions connected by vertical transverse spaced walls 50 defining a pocket 23 adapted to accommodate the bottom head of the center pin.

In carrying out my invention, I provide the body and truck bolsters with aligned center pin receiving openings 21 and 22. The opening 22 of the truck bolster extends through the bearing block 16. As most clearly shown in Figure 2, the pocket 23 is of greater width than the diameter of the opening 22 and serves to accommodate the head portion at the lower end of the center pin or retaining element, as hereinbefore pointed out, which is employed to connect the two bolsters. An annular shoulder 24 is thus provided at the junction of the pocket 23 and the opening 22. The major portion of the sleeve section 12 of the

body bolster is of larger diameter than the opening 21, thereby providing a pocket 25, and an annular shoulder 26 at the bottom of said pocket adjacent the pin receiving opening 21.

5 My improved center pin proper comprises a pair of counterpart outer sections A—A and a central filler or spreading member B. The sections A of the pin are of identical construction, and the two sections, when assembled, 10 form a substantially tubular connecting element. Each of the sections A is provided with an exterior flange 27 at the bottom end thereof, which forms a part of the head member at the lower end of the center pin.

15 The flange members 27 are adapted to cooperate with the shoulder 24 to restrict the upward movement of the sections A. Each section A is also provided with an exterior flange 28 at the upper end thereof, adapted 20 to cooperate with the shoulder 26 of the body bolster, the flanges 28 of the two sections A together forming an annular head member at the upper end of the pin. The portions of the 25 members A, between the top and bottom flanges thereof, form the shank of the center pin. The shank portion is of substantially cylindrical shape in horizontal cross section and fits within the center pin openings 21 and 22 of the two bolsters when the spreading 30 or filler element B is assembled therewith.

35 The filler member B is in the form of a substantially cylindrical bar or rod and is adapted to fit snugly within the sections A, each 40 of the sections being provided with a seat 29 adapted to accommodate the corresponding side of the member B, the two seats 29 together forming a vertical bore at the center of the pin, of cylindrical horizontal cross section. The bottom end of the member B is 45 tapered, as indicated at 30, to facilitate insertion of said member between the sections A of the pin. At the upper end, the member B is provided with a head 31 adapted to seat on top of the pin to hold the member B 50 against downward movement and prevent accidental displacement of the same. The head 31 may also be provided with an eye member 32, as shown, with which a tool may be engaged to facilitate removal of the filler member B.

55 As shown in Figure 2 of the drawings, the flanges 28 at the upper ends of the sections A have the edge faces cut away, as indicated at 33, to provide in effect an upwardly tapered head member. By thus cutting away the flanges, the sections A may be rocked inwardly on each other in assembling the same 60 with the bolsters, without actual contact between the flanges and the side walls of the pocket 25. Immediately below the flange portions 65 28, the sections A are cut away, as indicated at 34, to provide in effect an annular groove which will clear the shoulder 26

when the sections are rocked in the manner pointed out.

At the upper end of the pin, the sections A have flat-faced contact along their inner edges, thereby preventing contraction of the upper end of the pin and at all times maintaining the flanges 28 in engagement with the shoulder 26 of the bolster 10. The inner edges of the sections A, at the bottom portions of the pin, diverge downwardly, as indicated at 35—35, thereby permitting inward rocking movement of the bottom portions of the sections A toward each other to effect contraction of the lower end of the pin when the filler member is not in position so as to permit insertion of the flange portions 27—27 through the center pin receiving openings 21 and 22 of the two bolsters. The openings 21 and 22 preferably have diametrically opposite side wall portions thereof cut away as indicated at 40—40 whereby the flange members 27—27 may be made of relatively great width to overlap the annular shoulder 24 to a maximum extent, the cut away portion 40—40 defining vertical guideways to accommodate the inner ends of the flanges at diametrically opposite sides of the pin.

In assembling my improved center pin with the bolsters of a railway car, the sections A are inserted as a unit through the pocket of the body bolster, with the inner edge portions 35 thereof in contact. The head section formed by the flanges 27 is thus contracted to an extent that the same will pass freely through the pin receiving openings 21 and 22 and guideways 40—40.

The two sections A are passed downwardly through the pin receiving openings 21 and 22 until the flanges 27 are disposed within the pocket 23 of the truck bolster beneath the annular shoulder 24. As will be evident, when the sections A of the pin are being assembled with the bolsters in the manner pointed out, the upper end portions of said sections will be spread apart slightly, thereby 110 tilting the head portions formed by the flanges 28. Clearance for passage of the parts through the pocket 25 and the opening 21 past the shoulder 26 while the parts are thus tilted, is provided by cutting away the flanges 28 and the shank portions of the members A adjacent said flanges, as hereinbefore 115 pointed out.

After the sections A have been assembled with the bolsters in the manner just described, 120 the filler or spreading member B is inserted between the sections through the pocket 25 of the body bolster. The insertion of the member B between the sections A is facilitated by the tapered bottom end portion of said member. As the member B is forced downwardly 125 between the sections A, the latter will be spread apart at their bottom ends and the flanges 27 thereof brought into overlapping relation with the annular shoulder 24. When 130

the filler member B has been fully inserted, the inner edge portions of the sections A at the upper portion of the pin will be in flat-faced engagement, as shown in Figure 2. As hereinbefore pointed out, the head member 5 31 of the filler B limits the downward movement thereof by engagement with the upper end portions of sections A.

As will be evident, when the parts have 10 been completely assembled, the two members A and the filler member B together form a substantially solid pin, the shank of which fills the center pin receiving openings 21 and 22 of the bolsters.

15 Considerable strength against shearing is provided in my improved center pin construction by bringing the inner edges of the sections A, at the upper end of the pin, into bearing contact. As the contacting portions of 20 the sections A extend a considerable distance below the upper end of the pin to a point adjacent the bearing connection between the two bolsters, the pin presents a cross sectional area at that point substantially the same as 25 the cross sectional area of the pin receiving opening, thereby providing the maximum resistance against shearing.

Although my improved pin has been described and shown as being assembled with the 30 bolsters by passing all the members thereof through the pocket of the body bolster into the pin receiving openings, it will be evident that the outer sections A may be assembled with the bolsters by reversing the same, end 35 for end, and inserting the same through the pocket 23 of the truck bolster, the flanges 27 being disposed uppermost and in contracted relation. After the members or sections A 40 have been thus assembled, the filler member may be inserted between the same, either through the opening of the body or the opening of the truck bolster. It is also possible to apply the filler member B through the opening of the truck bolster, with the sections A 45 assembled, as shown in Figure 2.

When the filler member B is applied from the bottom, it is evident that some means must be provided to prevent removal of the same in a downward direction. Any well known retaining means may be employed for this purpose.

When it is desired to separate the body and truck bolsters of a car, it is merely necessary to withdraw the filler member B of my improved center pin construction and then contract the end of the pin provided with the flanges 27 and withdraw the sections A from the pin receiving openings.

60 While I have herein shown and described what I consider the preferred manner of carrying out my invention, the same is merely illustrative and I contemplate all changes and modifications that come within the scope of 65 the claims appended hereto.

I claim:

1. In car construction, the combination with body and truck bolsters having aligned center pin receiving openings; of a multipart center pin including outer members and a 70 filler member, said outer members each being headed at opposite ends and having shouldered engagement with the bolsters, said filler member holding the multipart pin expanded and maintaining the shouldered engagement 75 thereof with the bolsters, said pin at one end thereof having the outer members cut away at the inner sides to allow contraction of said end of the pin when the filler member is removed to permit insertion of said headed end through the pin receiving openings.

2. In car construction, the combination with body and truck bolsters having aligned center pin receiving openings; of a center pin composed of members headed at opposite ends 80 and a central filler member, said headed portions having shouldered engagement with the bolsters, said headed members having engagement with each other at one end of the pin to limit contraction of the head portion at said 85 end to maintain shouldered engagement thereof with the cooperating bolster, the headed members at the other end of said pin being separated by said filler member to maintain the shouldered engagement thereof with the 90 other bolster, said members being displaceable inwardly at said last named end portion when said filler member is removed to allow contraction of the corresponding head portion thereof, to permit insertion of said head 95 portion through the bolster center pin openings.

3. In car construction, the combination with body and truck bolsters having aligned center pin receiving openings and shoulders 100 adjacent each opening; of a center pin comprising two outer members and a central filler member, each outer member having head portions at opposite ends thereof having engagement with the shoulders of said bolsters, said members having engagement with each other at one end of the pin and being separable at the other end when said pin is disposed within said openings so as to engage 105 said head portions with the shoulders of both 110 bolsters, said filler member being removable and adapted to hold said members spread apart when inserted therebetween, the last named end of said pin being contractable when said filler member is removed to permit 115 passage of the headed portion at the corresponding end thereof through said pin receiving openings.

4. In car construction, the combination with body and truck bolsters having center 120 pin receiving openings provided with retaining shoulders adjacent said openings; of a center pin having heads at opposite ends thereof, having shouldered engagement with 125 said shoulders of the respective bolsters and 130

a shank portion disposed within said openings, said pin including an inner member and outer members disposed about said inner member, said outer members having the head portions of the pin formed thereon, said outer members at one end of the pin having engagement with each other to maintain the head portion at said end engaged with the corresponding shoulders, and said outer members at the other end of the pin being held separated by said inner member to maintain the shouldered engagement of the corresponding head portions with the adjacent bolster shoulders, said last named end of the pin being contractable when said inner member is removed to permit free passage of the corresponding headed portion thereof through said pin receiving openings.

5. In car construction, the combination with body and truck bolsters having aligned center pin receiving openings and shoulders adjacent each opening; of a center pin comprising a pair of counterpart outer members, and a removable filler member, each of said counterpart outer members being headed at opposite ends, said pin having a central bore formed partly in each of said counterpart members to accommodate said filler member, the counterpart members of said pin having contact with each other at one end of the pin and being cut away on their inner sides at the other end of said pin to permit contraction of the corresponding head member thereof to allow passage of said head member through the pin receiving openings, said last named end of the pin being held expanded by said filler member when inserted in the bore of said pin to maintain said last named head engaged with the shoulder of the corresponding bolster.

6. In car construction, the combination with body and truck bolsters having aligned center pin receiving openings and a retaining shoulder adjacent each opening; a center pin member including a pair of counterpart partly tubular sections together forming a complete tubular member, and a filler member within said tubular member, each of said counterpart sections having exterior flanges at opposite ends thereof forming head members cooperating with said retaining shoulders of both bolsters, the portions of said tubular members intermediate the heads thereof forming the shank portion of the pin and extending through said pin receiving openings, the inner edges of said tubular sections being in contact at one end of the pin and the inner edges at the other end portion of the pin being held separated by said filler member when inserted within the sections of the tubular member to maintain the head member at the corresponding end engaged with the retaining shoulder of the corresponding bolster, said last named end being contractable when said filler member is re-

75 moved by rocking said sections inwardly on each other to permit insertion of said head portion through the bolster center pin openings.

In witness that I claim the foregoing I have hereunto subscribed my name this 21st 70 day of January, 1929.

STACY B. HASELTINE.
